CLAIM

The ornamental design for an exercise support device, as shown and described.

DESCRIPTION

FIG. 1 is a top perspective view of the exercise support device of the invention, in an operative mode;

FIG. 2 is a right side elevation view;

FIG. 3 is a front end view;

FIG. 4 is a top plan view;

FIG. 5 is a left side elevation view;

FIG. 6 is a back end view; and,

FIG. 7 is a top perspective view of the exercise support device of the invention in a folded storage mode.
